UNITED STATES PATENT OFFICE.

LESLIE P. GREEN, OF CHICAGO, ILLINOIS.

EXCAVATOR.

Application filed June 24, 1921. Serial No. 479,990.

To all whom it may concern:

Be it known that I, LESLIE P. GREEN, a citizen of the United States, and a resident of the city of Chicago, county of Cook 5 and State of Illinois, have invented certain new and useful Improvements in Excavators, of which the following is a specification.

My invention relates to improvements in 10 excavators, and has for its object the provision of an improved construction of this character which is simple and efficient in use.

Other objects will appear hereinafter.

15 The invention consists in the combinations and arrangements of parts hereinafter described and claimed.

The invention will be best understood by 20 reference to the accompanying drawings forming a part of this specification, and in which,

Fig. 1 is a side view of an excavator embodying the invention.

Fig. 2 is an end view thereof.

25 Fig. 3 is a rear view of the excavating bucket, and

Fig. 4 is a detail view of a stop member mounted in the construction.

The preferred form of construction as 30 illustrated in the drawings comprises a suitable supporting cable 5 which is stretched over the area to be excavated in the usual manner. A carriage 6 equipped with grooved supporting wheels 6' is ar- 35 ranged to travel on said supporting cable over the area to be excavated in the usual manner, and a stop clamp 7 is adjustably secured to the cable 5 so as to stop the travel of said carriage at any desired point 40 in its travel on said cable.

Two triangular rocker members 8 are pivoted at 9 on carriage 6 and links 10 and 11 are pivoted, as shown, to the corners of members 8 on opposite sides of the pivots 45 9. An excavating bucket 12 is pivoted, as shown, to the lower ends of the links 10 and 11 and is balanced to carry its load. A draw cable 13 is connected to cause the carriage 6 and the bucket 12 to traverse the 50 area to be excavated. The cable 13 is provided with two branches 14 and 15. The branch 14 consists of two diverging cable strands leading and attached to eyes 14' and on the forward edges of the excavating 55 bucket as shown. The branch 15 consists of two diverging strands passing around

the grooved guide pulleys 16 on carriage 6 and connected with eyes 17 on the rocker members 8 as shown, the branches 15 passing under and beyond the pivotal axis 9. Stops 60 18 and 19 are arranged on carriage 6 to limit the rocking movements of the members 8 in either direction. The excavating bucket 12 is provided with a swinging tail gate 20 pivoted thereto and carrying a spring held 65 latch bolt 21 adapted to engage a latch bar 22 as indicated. A tripping cable 23 is attached to the latch bolt 21 and also to an eye 24 on the under side of carriage 6, the arrangement being such that 70 when the excavating bucket 12 dumps as indicated in dotted lines in Fig. 1, the tail gate 21 will be automatically released and swing into open position to discharge the contents of the bucket.

75 In operation, the cables 5 and 13 are manipulated in the usual way to permit the carriage and bucket to slide down cable 5 under the influence of gravity over the area to be excavated, whereupon cable 5 is slackened and cable 13 is operated as a draw cable to draw the excavating bucket back over the area to be excavated, filling the same with material in the usual way, said material being lifted by tightening cable 5 80 and also by the upward inclination thereof and carried in the bucket 12 until the stop 7 is encountered, said stop being positioned at the point where it is desired to dump the excavating material. When the 85 stop 7 is encountered by the carriage 6, further travel of said carriage is prevented, whereupon the bucket 12 will be caused to swing forwardly by the tension on cable 13. This will throw the tension on to the cable 90 strands 15 and thence on to the eyes 17 on the rocker members 8. The cable strands 15 passing under and beyond the pivoted points 9 will cause the rocker members 8 to rock rearwardly into the dotted line position as indicated in Fig. 1. This will cause 95 links 10 to elevate the forward end of bucket 12 and links 11 to lower the rearward end thereof, thus automatically opening the tail gate 20 and dumping the contents of said bucket as indicated in dotted lines in Fig. 1. When tension on cable 13 is relieved, the bucket 12 assumes its normal position by the action of gravity and because it is balanced to do so, such assumption being in any event forced by contact 100 of the bucket with the ground as the car-

riage 6 slides down the cable 5. Renewal of the drawing force on cable 13 will repeat the operation, filling the excavating bucket and dumping the same as above outlined. If 5 the cable strands 14 are adjusted a little longer than indicated, the carriage will be drawn along cable 5 by the tension in cable strands 15 until the stop is encountered, when the dumping action will take place as 10 above. The added "slack" in cable strands 14 permits more free dumping of the bucket and thus a complete upending thereof to facilitate discharge. In either arrangement, a simple and effective excavating mechanism 15 is provided which will carry its load to the desired point and then effectively dump and discharge the same.

While I have illustrated and described the preferred form of construction for carrying 20 my invention into effect, this is capable of variation and modification without departing from the spirit of the invention. I, therefore, do not wish to be limited to the precise details of the construction set forth, 25 but desire to avail myself of such variations and modifications as come within the scope of the appended claims.

Having described my invention, what I claim as new and desire to secure by Letters 30 Patent, is:—

1. An excavator comprising a supporting cable; a carriage travelling thereon; a stop for said carriage; an excavating bucket 35 swingingly suspended on said carriage; means on said carriage for dumping said bucket rearwardly; a draw cable operatively attached to said bucket and said dumping means and arranged to dump said bucket rearwardly when said carriage encounters 40 said stop; a tail gate for said bucket; and means for automatically opening said tail gate upon dumping of said bucket, substantially as described.

2. An excavator comprising a supporting 45 cable; a carriage travelling thereon; a stop for said carriage; a rocker member pivotally mounted on said carriage; supporting links pivoted to said rocker member; an excavating bucket pivotally carried by said links, 50 said bucket being arranged to be dumped rearwardly by rocking of said member; a draw cable operatively connected with said bucket and with said rocker member; a tail gate for said bucket; and means for automatically opening said tail gate upon dumping 55 of said bucket, substantially as described.

3. An excavator comprising a travelling 60 carriage; an excavating bucket supported thereon; a draw cable having two branches, one leading to said bucket and the other to said carriage; means operable by a shift of tension from one of said branches to the other for dumping said bucket rearwardly; a

tail gate for said bucket; and means for 65 automatically opening said tail gate upon dumping of said bucket, substantially as described.

4. An excavator comprising a supporting cable; a carriage travelling thereon; a stop 70 for said carriage on said cable; a draw cable having two branches, one leading to said carriage and the other to said bucket; means operable by a shift of tension from one of 75 said branches to the other for dumping said bucket rearwardly; a tail gate for said bucket; and means for automatically opening said tail gate upon dumping of said bucket, substantially as described.

5. An excavator comprising a supporting 80 cable; a carriage travelling thereon; a stop for said carriage on said cable; triangular rocker members pivoted on said carriage; supporting links pivoted to said rocker members on opposite sides of the pivot 85 thereof; an excavating bucket suspended on said links and balanced to carry its load; a draw cable having two branches, one branch leading to said bucket and the other to said rocker members, and adapted and arranged 90 to rock said rocker members rearwardly when tension is shifted thereon; a tail gate for said bucket; and means for automatically opening said tail gate upon dumping of said bucket, substantially as described. 95

6. An excavator comprising a supporting cable; a carriage travelling thereon; a rocker member on said carriage; an excavating bucket supported on said rocker member to be dumped rearwardly by rocking thereof; 100 means for rocking said rocker member; a tail gate for said bucket; and means for automatically opening said tail gate upon dumping of said bucket, substantially as described. 105

7. An excavator comprising a supporting cable; a carriage travelling thereon; a stop for said carriage on said cable; a rocker member pivoted on said carriage; an excavating bucket suspended on said rocker member on opposite sides of the pivot thereof; a draw cable having two branches, one leading to said bucket and the other to said rocker member and adapted to rock said rocker member to cause rearward dumping 110 of said bucket upon stopping of said carriage; a tail gate for said bucket; and means for automatically opening said tail gate upon dumping of said bucket, substantially as described. 115

In testimony whereof I have signed my name to this specification in the presence of two subscribing witnesses.
